UNITED STATES PATENT OFFICE

2,528,949

STOOL HAVING REVOLVING SEAT

Carl J. Engstrom, Michigan City, Ind., assignor
to The Royal Metal Manufacturing Company,
Chicago, Ill., a corporation of Illinois

Application September 13, 1945, Serial No. 616,039

6 Claims. (Cl. 155—95)

1

This invention relates to furniture construction and, more particularly, the present invention relates to a stool and particularly to a revolving stool such, for example, as a bar stool, although certain phases of the invention are also applicable to other articles of furniture including so-called counter or pedestal stools, store stools, kitchen stools and the like.

In the prior art bar and like stools which have embodied a rotatable or revolving seat, it has been common practice to rotatably mount the seat on the supporting frame of the stool, and to interconnect the seat and the supporting frame by means of a single center swivel pin or bolt or the like. However, as such stools are subjected to severe usage and are frequently rocked on their supporting frames and tipped over, the swivel pin or bolt or like interconnection between the seat and the supporting frame tends to work loose and tends to become bent or to be sheared or to break off.

Another object of the present invention is to provide a new and improved stool or like article of furniture embodying a novel but relatively simple and efficient construction for rotatably mounting the seat portion of the new stool upon the supporting frame or base thereof and in such a manner that the seat will rotate freely upon and relative to the supporting frame but will not become loose relative thereto or be disconnected therefrom as the stool is subjected to various stresses and strains in use.

A further object of the invention is to provide a novel construction for interconnecting the supporting frame or base of the new stool and the anti-friction bearing assembly upon which the seat of the new stool is rotatably mounted.

Still another object of the invention is to provide a novel construction for detachably interconnecting the anti-friction bearing assembly of the new stool and the seat cushion base embodied in the new stool.

Another object of the invention is to provide a novel, strong and sturdy interconnection between the cross pieces of the tubular metal legs of the supporting frame or base of the new stool and which interconnection between said cross pieces is effected without removing any of the tubular metal stock of said cross pieces or otherwise weakening said cross pieces at their point of intersection.

Other objects of the present invention will be apparent from the following description and claims and are illustrated in the accompanying drawings which, by way of illustration, show preferred embodiments of the invention and the principles thereof and what I now consider to be the best mode in which I have contemplated applying

2

those principles. Other embodiments of the invention embodying the same or equivalent principles may be used and structural changes may be made as desired by those skilled in the art without departing from the present invention and the purview of the appended claims.

In the drawings,

Fig. 1 is a side elevational view of a bar stool embodying the present invention;

10 Fig. 2 is an enlarged central sectional view showing the construction of the seat of the new stool and the construction of the novel anti-friction bearing assembly for rotatably mounting the seat upon the supporting frame or base of the new stool, only a part of the supporting frame or base of the stool being shown;

15 Fig. 3 is a detail plan view of the top central portion of the connection between the cross pieces of the tubular metal legs which are embodied in the supporting frame of the stool shown in the drawings;

20 Fig. 4 is a top plan view on line 4—4 in Fig. 2 showing the construction of the annular plate or pan which forms the bottom wall of the seat and by means of which the seat is attached to the anti-friction bearing assembly;

25 Fig. 5 is a sectional plan view on line 5—5 in Fig. 2 illustrating the construction of the anti-friction bearing assembly which is embodied in the new stool for rotatably mounting the seat thereof upon its supporting frame; and

30 Fig. 6 is an enlarged sectional detail view on line 6—6 in Fig. 5 illustrating the construction of the anti-friction bearing assembly for interconnecting the seat and the supporting frame of the new stool; this figure also illustrating the novel manner in which the anti-friction bearing assembly is connected to the supporting frame or base of the new stool.

35 40 A typical and preferred embodiment of the present invention, in the form of a bar stool embodying a revolving seat, is illustrated in the drawings, wherein it is generally indicated at 10, and comprises a supporting base or supporting

45 frame, which is generally indicated at 11, and a seat which is generally indicated at 12. The supporting base or frame 11 of the new stool comprises a pair of tubular metal legs 13 which are formed of a single U-shaped piece of suitably plated tubular metal, the tubular legs 13 being interconnected at their upper ends by an inter-

50 connecting cross piece or bight portion 14. The supporting frame or base 11 of the new stool also includes a second pair of suitably plated tubular metal legs 15 which are interconnected at their upper ends by an interconnecting cross piece or bight portion 16.

55 In order to interconnect the cross pieces or

bight portions 14 and 16 which interconnect the tubular legs 13 and 15, respectively, the tubular metal stock of which said cross pieces are formed is swaged out and flattened, as at 17, thereby providing cooperating recesses 66 in said cross pieces 14 and 16 at the point where said cross pieces 14 and 16 intersect each other. Thus, the flattened and swaged out portion of the lower cross piece 16 extends up into the recess 66 provided in the upper cross piece 14 and the flattened and swaged out portion of the upper cross piece 14 lies within the recess 66 provided by the flattened and swaged out portion 17 of the lower cross piece 16. In this manner a strong and sturdy interconnection is effected between the cross pieces 14 and 16 of the tubular metal legs 13 and 15, respectively, without cutting out or removing any of the tubular metal stock in the cross pieces 14 and 16 and without forming any bolt holes in said cross pieces 14 and 16 at their points of intersection and which, if so formed, would weaken the cross pieces 14 and 16 at their points of intersection.

The interconnecting or cross pieces 14 and 16 which connect the tubular legs 13 and 15, respectively, are provided with lower and upper aligned holes or openings 41 and 42, respectively, in the metal stock thereof. The metal stock of those portions of the tubular cross pieces 14 and 16 in which the upper openings 42 are formed is depressed as at 43 around the marginal edges of the openings 42. The threaded stems 39 of so-called T-nuts project downwardly through these openings 42, the base flanges 38 of these T-nuts being welded, as by projection welding, to the lowermost plate or raceway 35 in the anti-friction bearing unit or assembly 20. Bolts 40 are inserted through the openings 41 in the lower walls of the tubular cross pieces 14 and 16 and are threaded into the threaded stems or shanks 39 of the T-nuts 39—38, as shown in Figs. 4 and 6. There are preferably four of the bolts 40 and T-nuts 38—39 providing the desired interconnection between the cross pieces 14 and 16 of the tubular legs 13 and 15, respectively, and the lowermost plate or anti-friction ball bearing raceway 35 in the anti-friction bearing unit or assembly 20.

Thus it will be seen that the supporting base or frame 11 is firmly but detachably attached to the anti-friction bearing unit or assembly 20, which will be described hereinafter, so that the tubular metal supporting frame 11 may be detached from the anti-friction bearing unit or assembly 20 for repair or replacement if and when necessary. The supporting base or frame 11 of the new bar stool is completed by an annular metal retaining member or bracing ring 19 which encircles the tubular metal legs 13 and 15 and which may be secured thereto by means of suitable fastening elements such as bolts or the like.

The seat 12 of the new bar stool 10 is of the revolving type, being rotatably mounted upon and secured to the supporting base or frame 11 by means of an anti-friction bearing unit or assembly 20, which will be described hereinafter. The seat 12 is comprised, in general, of a seat cushion base 21 which is mounted on the anti-friction bearing unit or assembly 20 and an upholstered seat cushion 22 which is detachably mounted on the seat cushion base 21 of the seat 12, all of which is discussed in greater detail in my co-pending application, Serial No. 754,465, filed June 13, 1947.

The seat cushion base 21 of the seat 12 in- 75

cludes a metallic frame member 23, which is preferably formed of shaped steel, and which is preferably but not necessarily annular in form since it may be made in other shapes or forms, depending upon the shape desired in the seat of the new stool. The annular metallic frame member 23 of the seat 12 has an inwardly extending horizontal annular flange 24 formed thereon at the bottom thereof and said annular frame member 23 also has an inwardly extending annular flange 25 formed thereon at the upper end thereof, Fig. 2, on which the seat cushion 22 is mounted as discussed in greater detail in my aforementioned co-pending application, Serial No. 754,465.

Also, the seat cushion base 21 of the seat 11 embodies a steel bottom plate or pan 29 which is attached to the annular member 23 of the seat base 21 and to the anti-friction bearing unit or assembly 20 in a manner which will be described presently. As shown in Fig. 4, this bottom plate or pan 29 is provided with a radially arranged series of depressed reinforcing ribs 30 which are formed integrally therein and which extend radially outwardly from a depressed annular center portion or reinforcing ring 31 also formed integrally in the bottom plate 29 (Figs. 4 and 6).

The depressed central portion 31 of the bottom wall or pan 29 of the seat 21 is attached in any suitable manner, as by spot welding, to an annular plate or disc 32 which is embodied in and forms the upper raceway of the anti-friction bearing unit or assembly 20. As shown in Figs. 2 and 6, the upper raceway plate 32 has a marginal edge portion which extends convexly upwardly and projects above the upper surface of the body of the raceway plate 32 so as to provide the upper wall of a ball bearing race which is embodied in the anti-friction bearing unit or assembly 20. The lower wall of this ball bearing race is provided by the marginal edge portion 34 of the lower raceway plate 35 which is embodied in the anti-friction bearing unit or assembly 20. As shown in Figs. 2 and 6, the marginal edge portion 34 of the lower raceway plate 35 extends upwardly around the marginal edge 33 of the upper raceway plate 32 and terminates just below the lower surface of the base plate or pan 29 of the seat 12. The anti-friction bearing unit or assembly 20 is completed by a row of anti-friction elements in the form of ball bearings 36 which are mounted in openings or pockets 67 provided therefor in a pair of flat metal ball retainer plates or discs 37. These ball retainer plates or discs 37 are arranged between the upper and lower plates 32 and 35, respectively, of the anti-friction bearing unit or assembly 20 and the ball bearings 36 work in the raceway provided by the marginal edge portions 33 and 34 of the upper and lower raceway plates 32 and 35, respectively.

The lower raceway plate 35 in the anti-friction bearing assembly or unit 20 is provided with an annular row of radially arranged openings 69 and each of the ball retainer plates or discs 37 is provided with a similar annular row of radially arranged openings 68, the openings 68 and 69 being disposed in alignment or registry with each other to enable a welding tool or electrode to be inserted therethrough so as to spot weld the uppermost raceway plate 32 to the depressed central portion 31 of the bottom pan or plate 29 of the seat 12.

In order to attach the base plate or bottom

pan 29 of the seat 12 to the annular member 23, which is embodied in the seat 12, countersunk or depressed bolt holes 55 are formed in the bottom plate or pan 29 and bolts 56 are extended upwardly through these openings or holes 55 in the pan 29 and into threaded engagement with the lower arms 58 of brackets 59 attached to the annular member 23, as discussed in greater detail in my aforementioned co-pending application, Serial No. 754,465.

The seat cushion 22 is releasably secured in position on the upper flange 25 of the annular member 23 by suitable means such as bolts 61 extending through the top arms 60 on the brackets 59 into threaded engagement with brackets 63 carried by the seat cushion 22, as is also discussed in greater detail in my aforementioned co-pending application, Serial No. 754,465.

The various parts or units of the new bar stool may be assembled and interconnected substantially as follows:

The base flanges 38 of the T-nuts 38-39 may be welded or otherwise fastened to the lower raceway plate 35 on the bottom side thereof. The anti-friction bearing assembly or unit 20 may then be assembled by arranging the two ball retainer plates or discs 37, with the anti-friction elements or balls 36 disposed in the pockets 67 therein, between the upper and lower raceway plates 32 and 35, respectively, and then spinning or otherwise bending the marginal edge portion 34 of the lower raceway plate 35 around the pre-formed marginal edge portion 33 of the upper raceway plate 32, as by means of a suitable spinning or die-forming operation.

The anti-friction bearing assembly or unit 20 may then be mounted upon the supporting base or frame 11 by arranging the flattened portion 17 of each of the cross pieces 14 and 15 of the tubular legs 13 and 15, respectively, in nested relationship with the recessed portion 66 of the other cross piece, as in Fig. 2, and with the threaded stems or shanks 39 of the T-nuts 38-39 projecting downwardly through the holes 42 in the cross pieces 14 and 16 of the tubular metal legs 13 and 15, respectively. The bolts 40 may then be inserted through the openings 41 in the lower walls of the cross pieces 14 and 16 and then screwed into the internally threaded stems or shanks 39 of the T-nuts 38-39 previously welded to the lower raceway plate 35 of the anti-friction bearing assembly or unit 20. In this manner the anti-friction bearing assembly or unit 20 may be mounted upon and attached to the tubular metal supporting frame 11 of the new stool while, at the same time, the tubular metal legs 13 and 15 and the cross pieces 14 and 16, respectively, thereof are firmly secured together.

The base plate or bottom pan 29 of the seat 12 may then be attached to the anti-friction bearing assembly or unit 20 by arranging the central depressed portion 31 of the base plate or pan 29 over the upper surface of the upper raceway plate 32 of the anti-friction bearing assembly 20 and then spot welding the upper raceway plate 32 of the anti-friction bearing assembly 20 to the base plate or bottom pan 29 of the seat 12. This may be accomplished by inserting a welding electrode through the registered openings 69 and 68 in the lower raceway plate 35 and in the ball retainer discs 37, respectively.

The combination reinforcing and attaching members 59 may be attached to the annular member 23 of the seat base 21, and on the inner

surface of said annular member 23, by welding the members 59 to the member 23.

Hence, it will be seen that the last operation involved in assembling the new stool is to mount the assembled seat cushion unit 22 and the base 21 of the seat 12 upon the base plate or bottom pan 29, it being understood that the depressed central portion 31 of the base plate or bottom 29 has previously been spot welded to the upper raceway plate 32 of the anti-friction bearing unit or assembly 20. This final operation of attaching the base plate or bottom pan 29 of the seat to the assembled seat cushion 22 and seat base 21 is accomplished by inserting the bolts 56 through the openings 55 in the base plate or bottom pan 29 and screwing them into threaded engagement with the arms 58 of the members 59.

When the seat 12 and the supporting frame or base 11 of the new stool are assembled and interconnected by the anti-friction bearing or assembly unit 20, the seat 12 is free to rotate or revolve readily upon the anti-friction bearing unit 20 or assembly relative to the supporting base or frame 11 and the tubular legs 13 and 15 which are embodied therein. At the same time, a strong and sturdy interconnection is thus effected between the seat 12 and the supporting frame 11 so that when the new stool is subjected to the shocks and stresses and strains to which bar and counter stools and the like are subjected in use, as when rocked or tipped over or otherwise roughly handled, the interconnection thus afforded between the seat 12 and the supporting base 11 effectively resists separation of the seat 12 from the supporting base 11 or loosening of the seat 12 upon the supporting base 11 and thus overcomes one of the difficulties experienced heretofore in the use of prior art bar stools. This arrangement likewise eliminates the concentration of the stresses and strains to which such stools are subjected upon a single interconnecting stem or casting between the seat of the stool and its supporting base as in the prior art and spreads such stresses and strains over a relatively wide area.

It will also be seen that the anti-friction assembly or bearing unit 20, and associated parts, embodied in the new stool provide a novel interconnection between the seat and the supporting base so that the seat may readily be rotated or revolved relative to its supporting base while being, at the same time, detachably attached thereto by a strong and sturdy interconnection which will effectively resist any tendency of the seat to be dislodged or broken or to be loosened from its supporting base if and when the stool is tilted or tipped over or otherwise subjected to the severe stresses and strains to which bar stools and other stools are subjected in use.

It will thus be seen from the foregoing description, considered in conjunction with the accompanying drawings, that the present invention provides a new and improved article of furniture in the form of a stool having the desirable advantages and characteristics, and accomplishing its intended objects, including those hereinbefore pointed out and others which are inherent in the invention.

While the invention has been illustrated and described as applied to a bar stool, it is contemplated that at least certain phases of the invention may take other forms and may be used in other articles of furniture including counter or so-called pedestal stools, display tables, store stools, and the like.

I claim:

1. An article of furniture comprising a supporting base including two U-shaped tubular leg members having bight portions intersecting in nested relationship, said leg members having openings formed therein exteriorly of said intersection of said leg members, an anti-friction bearing assembly mounted on said supporting base above said intersecting bight portions, said bearing assembly including an upper and a lower anti-friction bearing raceway plate, screw members extending through said openings formed in said tubular leg member and attaching said lower raceway plate to said supporting base, and a seat mounted upon said anti-friction bearing and rotatably supported thereby on said supporting base, said seat including a bottom member having a depressed central portion attached to the central portion of said upper raceway plate, said upper and lower raceway plates being rotatable relative to each other and being operatively connected together exteriorly of said screw members and of the attachment of said bottom member to said upper raceway plate.

2. An article of furniture comprising a supporting base, an anti-friction bearing assembly mounted on said supporting base, said bearing assembly comprising an upper bearing plate, a lower bearing plate and a plurality of bearing balls mounted between said plates, each of said bearing plates having annular-shaped raceways formed in the peripheral edge portion thereof; said raceways in said plates being complementary to each other and being positioned in axial alignment with each other, said balls being positioned in said raceways, the continuous peripheral edge portion of one of said plates extending around and overlapping the peripheral edge portion of the other of said plates to thereby limit the outward movement of said plates relative to each other in any direction, and a seat member mounted on said upper bearing plate for support by said bearing assembly and said supporting base.

3. An article of furniture comprising a supporting base, an anti-friction bearing assembly mounted on said supporting base, said bearing assembly comprising a bottom bearing plate, an upper bearing plate rotatably mounted relative to said bottom plate, and a plurality of bearing balls, said plates being positioned in alignment with each other in parallel planes, the peripheral edge portions of said plates being deformed outwardly away from each other to afford convex annular-shaped surfaces on the outer faces thereof and concave annular-shaped raceways on the adjacent faces thereof, said balls being mounted in said raceways between said plates, the peripheral edge portion of one of said plates extending around the peripheral edge portion of the other of said plates to thereby hold said two plates together, said bottom plate being attached to said supporting base exteriorly of the center of said bottom plate, and a seat member mounted on said upper plate for rotation therewith relative to said bottom plate and said supporting base, said seat member having a portion attached to said upper plate within the outline of the deformed portions on said upper plate, said portion of said seat member being complementary in shape to the portion of said outer face of said upper plate within the outline of said deformed portions.

4. An article of furniture comprising a supporting base, an anti-friction bearing assembly mounted upon the said supporting base, and a seat mounted upon the said anti-friction bearing. 75

assembly and including a bottom wall, the said anti-friction bearing assembly including a top wall member permanently attached to said bottom wall of said seat and including a bottom wall member detachably attached to said supporting base, said top wall and said bottom wall of said anti-friction bearing assembly being rotatable relative to each other and being operatively connected together radially exteriorly of said attachment to said seat and said supporting base.

5. An article of furniture comprising a supporting base, an anti-friction bearing assembly mounted upon said supporting base, and a seat
15 mounted upon said anti-friction bearing assembly and including a bottom wall comprising a metal plate having a depressed central portion, said anti-friction bearing assembly including an upper raceway plate welded to said depressed central portion of said bottom wall of said seat, a lower raceway plate attached to said supporting base, a pair of anti-friction bearing retainer discs arranged between said upper and lower raceway plates, and a row of anti-friction bearings rotatably mounted in said retainer discs, said upper raceway plate being rotatable relative to said lower raceway plate and including a downwardly extending marginal edge portion having a convex curvature on its upper side, said lower raceway plate having an upwardly extending marginal edge portion extending partially around and over said downwardly extending marginal edge portion of said upper raceway plate on the outer side thereof so as to secure said upper and lower raceway plates together and secure said retainer discs and said anti-friction bearings between said plates.

6. An article of furniture as defined in claim 4 in which the said bottom wall of the said seat is in the form of a metal plate and in which the 40 said upper member of said anti-friction bearing assembly is in the form of an anti-friction bearing raceway plate welded to the said bottom wall of the said seat, and in which the said lower member of the said anti-friction bearing assembly 45 is in the form of an anti-friction bearing raceway plate detachably attached to the said supporting base radially outwardly from the center of said lower member.
